UNITED STATES PATENT OFFICE.

ALBERT J. ELDON, OF MOUNT VERNON, NEW YORK, ASSIGNOR TO PARAMOUNT RUBBER CONSOLIDATED, INC., OF TUCKAHOE, NEW YORK, A CORPORATION OF DELAWARE.

DESIGN FOR AN EDUCATIONAL BALL.

Application filed January 25, 1924. Serial No. 8,423. Term of patent 14 years.

To all whom it may concern:

Be it known that I, ALBERT J. ELDON, a citizen of the United States, residing at Mount Vernon, in the county of Westchester and State of New York, have invented a new, original, and ornamental Design for an Educational Ball, of which the following is a specification, reference being had to the accompanying drawing, forming a part thereof.

The drawing is a perspective view of a ball made in accordance with my design.

I claim:

The ornamental design for an educational ball substantially as shown in the drawing hereof.

ALBERT J. ELDON.
